BILFFOLD AND THE LIKE

William H. St. Thomas and Otto D. Weydener,
Gloversville, N. Y., assignors to E. J. Wilkins
Co., Gloversville, N. Y., a corporation of New
York

Application July 23, 1937, Serial No. 155,204

3 Claims. (Cl. 150—38)

This invention relates to billfolds and the like. The objects of the invention are to provide an improved billfold having a captive or tethered receptacle; to provide a ready and simple means for extracting the contents of a pocket and make possible the selection of the wanted item without having to handle the entire contents of the pocket; to provide ready access to numerous credentials; to provide maximum freedom of movement of the receptacle within its range of tethering; to minimize difficulty of operation; to lessen the likelihood of tearing the receptacle from the billfold; to provide a novel construction of tether for the receptacle; to obtain maximum strength of connection between the tether and receptacle at the withdrawn position of the receptacle; to provide a relatively short flexible connection between the inner end of the member and the fixed part of the tether; to secure simplicity of construction and operation; and to obtain other advantages and results as may be brought out in the following description.

Drawing:—

Figure 1 is a perspective view of billfold embodying our invention and showing the captive member in its normal position of rest within its pocket;

Figure 2 is a similar perspective view with the captive member withdrawn as far as its tethering will permit;

Figure 3 is a partial view of the billfold but with portions broken away and in section for showing the tethering construction;

Figure 4 is an elevation viewing the tethering means from the opposite face seen in Figure 3 with a portion of the billfold shown as folded upward out of the way to give a clear vision of the tethering construction; and

Figure 5 is a sectional view taken longitudinally 40 of the billfold as upon line 5—5 of Figure 1.

Description:—

In the specific embodiment of the invention illustrated in the said drawing, reference numeral 10 designates what may be termed the body portion or main longitudinal wall of the billfold. On one side of this wall 10 is provided another wall 11 which constitutes the outside wall of the billfold and between which two walls bills (paper money) or other items may be introduced. Particular disclosure shows an intervening partition 12 between the main wall or body portion 10 and the outside wall 11 for separating different denominations of bills or for other papers. This feature, however, is mentioned only because it is illustrated and not be-

cause of its necessary inclusion as part of the invention. It will be observed that walls 10 and 11 and partition 12 provide pockets therebetween which open along the entire longitudinal upper edge of the billfold. In use, the billfold is doubled at its middle at a line transverse to the said longitudinal edge, and each end portion of the billfold at the inside face of body portion 10 may be provided with pockets opening toward the line of doubling of the billfold. The present invention 10 is shown in association with the pocket thus formed at the righthand end of the billfold illustrated in the drawing. The pocket designated by numeral 13 is conveniently formed by a wall 14 which also constitutes a part of the inner wall 15 of the billfold. In the precise showing of the drawing, the lower front edge of this wall 14 is included beneath a turned-up edge or hem 15 of back wall 11 and held by a line of stitching 16. The said wall 14 is bent over the longitudinal 20 upper edge of body portion 10, and may, if desired and as shown continue downwardly behind the said wall 10 to also be stitched within hem 15 by the same line of stitching 16. These various details of the billfold construction are described merely to aid in understanding the drawing. The essential consideration is merely that a pocket is provided and the means shown is only one of many for obtaining a pocket in a billfold.

Within pocket 13 is slidably positioned a captive receptacle 17. This receptacle may assume various shapes and get various details of construction. In the particular illustration said receptacle is shown with a back member 18 substantially the width of pocket 13 so as to have a 35 sliding fit with respect thereto. The forward end of the back member 18 continues to form a flap 19 which, when the pockets are closed can be positioned flatwise over a pocket and the otherwise exposed face of the inner wall 14, and 40 held in such flatwise position by means of a loop 20 on said face under which a tab 21 shown attached to the flap, may be inserted. The member 17 may likewise have at its front side a frame edging 22 and a replaceable transparent front 45 face 23 held beneath the said edging. The edging is preferably held taut as by a line of stitching 24 next the longitudinal side edges and inner end edge of the backing 18. Backing 18 and said transparent member 23 with its edging 22 combine to form a convenient receptacle for identification cards or other items.

At the inner end of captive member 17, is provided an extension 25 either integral with or attached to the backing 18 of said member and pro- 55

viding a convenient means for securing a metallic rectangular loop 26 with respect to said member 17 with the greatest length of the loop substantially normal to the length of said receptacle. 5 The loop 26 will accordingly travel back and forth with the receptacle as the receptacle is slid into or pulled out of pocket 13. Tethering of receptacle 17 is effected by means of suitable means providing a limited movement 10 of the loop longitudinally above the pocket. The means shown comprises a double thickness of tape or the like 27 with one bar of the loop riding between two plies of the tape and the tape having width substantially the length of the loop. Said 15 tape is secured at its ends to the inner wall 14 of the billfold where it is secured by line of stitching 28. The other end of the tape is secured to the same wall 14 of the billfold by line of stitching 29. Inasmuch as extension 25 carrying the loop 20 spaces the loop a distance from the receptacle portion of member 17, the attachment of the inner end of tape 27 by stitching 29 may conveniently be a distance from the end of the pocket corresponding to the length of said extension 25 and said extension will therefore double, as shown in Figure 5, when the receptacle is slid home within pocket 13. The distance which the captive member 17 may be withdrawn from its pocket 13 is governed by the position of a line of 30 stitching 30 connecting the two plies of tape 27 toward the open end of pocket 13. When the captive member is drawn outwardly, loop 26 seats at the end of the tape retaining means immediately adjacent the said line of stitching 30 which 35 secures the plies of the tape together, and the loop is thus held in a position normal to the length of the tape, captive member and billfold, and the fact that extension 25 is short with the inner end of the receptacle still within the confines of 40 pocket 13, the said receptacle is kept from materially sagging and is in proper position to be readily slid back into its pocket. Furthermore, the tape-like retaining means 27 is attached to the inner wall of the billfold and consequently 45 any strain applied tending to pull the receptacle away from the billfold has no tendency to pull the tape away from flatwise engagement with the wall to which it is attached, and likelihood of tearing either the said member or the wall to 50 which it is attached is minimized. Furthermore, the fact that loop 26 is free to slide back and forth obtains the greatest ease of operation and

freedom of movement of the captive member within the range of its tethering. Finally, attention is directed to the fact that the tape 27 constitutes a flexible loop longitudinal of the billfold and that the relatively rigid loop 26 slides freely with respect thereto and may teeter back and forth according to the direction of pull transmitted by the flexible extension 25 from the receptacle. The sliding of a relatively loose loop within a loop and actuation thereof to turn toward the direction of pull, obtains very easy sliding and avoids any difficulty in withdrawing or returning the receptacle with respect to its pocket. 5

We claim:—

1. A billfold or the like having a pocket, a member tethered in said pocket slideable into and out of the same, and tethering means comprising a looped tape within said pocket secured adjacent the open and closed ends thereof, said tethering 20 means also comprising another loop transverse to and slideable on the first said loop, and a flexible extension secured to the slideable loop and to the tethered member whereby said flexible extension may fold into a retracted position when fully inserted in the said pocket and forming a longitudinal continuation of the member when fully extended. 15

2. A billfold or the like having a pocket, a member tethered in said pocket slideable into and 30 out of the same, and tethering means comprising a tape within said pocket secured adjacent the open and closed ends thereof, said tape comprising a flexible loop the forward end of which is rearward from the forward secured end of the 35 tape adjacent the open end of the pocket, and a transverse loop slideably mounted within said loop of the tape and thereby connecting said tethered member slideably with respect to said tape, said tethering member having a flexible extension by 40 which said transverse loop is attached thereto. 30

3. A billfold or the like according to claim 1, wherein said tethered member is made up of a plurality of parts, namely, a back section, a frame section, a transparent member detachably 45 inserted between said frame and back sections, and a flap extending forwardly from the back section beyond the frame section to form a finger grip to manipulate the member. 50
